UNITED STATES PATENT OFFICE.

DAVID SHIVELL, OF ARLINGTON, INDIANA.

VEHICLE-TOP.

SPECIFICATION forming part of Letters Patent No. 623,186, dated April 18, 1899.

Application filed November 5, 1898. Serial No. 695,617. (No model.)

To all whom it may concern:

Be it known that I, DAVID SHIVELL, a citizen of the United States, residing at Arlington, in the county of Rush and State of Indiana, have invented certain new and useful Improvements in Vehicle-Tops, of which the following is a specification.

My present invention consists in certain improvements upon that shown and described in my Letters Patent No. 488,459, dated December 20, 1892. A vehicle-top embodying my said invention will be first fully described and the novel features thereof then pointed out in the claims.

Referring to the accompanying drawings, which are made a part hereof and on which similar reference characters indicate similar parts, Figure 1 is a side elevation, with some portions broken away, of a vehicle-top embodying my said invention; Fig. 2, a top or plan view of the same with the coverings of said top removed; Fig. 3, a central sectional view of the same in the position shown in Fig. 1 as seen from the dotted line 3 3 in Fig. 2; Fig. 4, a vertical sectional view as seen from the dotted line 4 4 in Fig. 1, except that the bow-like support which sustains the middle of the top lining is lowered, as when the parts are in position to move the side curtains; Fig. 5, a similar view to the upper portion of Fig. 4, except that said support to the top lining is raised and in position; Fig. 6, a fragmentary view, on a somewhat enlarged scale, similar to a portion of Fig. 5; Fig. 7, a detail view, on the same scale as Fig. 6, as seen from the dotted line 7 7 in Fig. 1; Fig. 8, a top or plan view of the front bow as shown in Fig. 7 with the top covering removed; Fig. 9, an inside view of one of the side curtains; Fig. 10, an inside view of the other side curtain; and Fig. 11 an edge view of the upper portion of one of the side curtains, showing one of the stiffening-plates and supports therefor.

The structure illustrated in said drawings is, generally speaking, substantially the ordinary form of top for that variety of vehicle generally denominated a "buggy" and may, except as to such parts as are otherwise specified, be understood to be of a usual and well-known construction. The invention is of course applicable to the tops of other classes of vehicles, and it is my intention to employ

it on all vehicles with which it is suitable to be used.

The structure consists generally of the seat 55 1, the bows 2, 3, and 4, the braces 5, the covering 6, a back curtain 7, and the side curtains 8 and 9.

Upon the bows are the wire tracks or guides 10, 11, 12, 13, and 14. These wires or tracks 60 are each fastened to the bows at the ends and stand out slightly therefrom throughout their respective lengths, except at the immediate point of attachment, as best shown in Fig. 8, so that the runners or connections on the curtains may easily pass along the same, as will be presently described.

In order that the curtains may have the necessary stiffness to move properly into and out of their closed position within the upper 70 portion of the vehicle-top, I provide them with a series of thin metal plates 15. In the arrangement shown the curtain 8 has three of these plates and the curtain 9 two of them. In order that they shall not interfere with the 75 folding back of the vehicle-top when that is desired, each series is secured together at the bottom by a pivot 16, so that they are enabled to move toward and from each other. Formed upon or attached to each of these plates at the 80 upper end is an eye 17, which is mounted upon the corresponding rod carried by the bows, the eyes on those plates on the curtains 8 resting upon the rods 11, 12, and 14, while the eyes of the plates on the curtain 9 are upon the 85 rods 10 and 13, as will be readily understood upon an inspection of the drawings. By the arrangement shown, with the rods arranged in pairs one above the other and the attachment as described, I am enabled to utilize 90 the entire width of the top of the structure in housing the side curtains when raised instead of half the width only, as in the construction of my former patent, the space in which as then constructed I have found to 95 be insufficient for the purpose.

In order to properly utilize this invention, it is necessary to provide more space between the cover and the top lining of the vehicle than normally exists to enable the curtains 100 to be moved at the time the movement is taking place. To this end I provide a bow-like support 18, which conforms to the shape of the upper portion of the middle bow 2, and

place the same inside the vehicle-top directly below the upper portion of said middle bow. At each end of this support I provide a catch 19, which is adapted to engage with a corresponding notch in said bow 2 when said support is raised to its highest position. Said catches are adapted to be readily detached, however, and the support lowered, and the lining of the top consequently permitted to 10 drop away from the bow, leaving a clear space between them in which the side and curtains may break freely. This is illustrated in Fig. 4, while the normal position is shown in Fig. 5.

Having thus fully described my said invention, what I claim as new, and desire to secure by Letters Patent, is—

1. The combination, in a vehicle-top, of the bows, a suitable covering thereon, a lining under said bows attached at the ends to the 20 end bows and adapted to be moved against or away from the middle bow, tracks or guideways secured to the said bows and extending entirely across the vehicle-top, said tracks or guideways upon the end bows being in pairs 25 and arranged one above the other, and side curtains mounted upon said tracks or guideways and adapted to be moved when not in use into the space in the upper portion of the vehicle-top above the lining one over the 30 other, and means for supporting the lining

and curtains against the under side of the middle bow when the parts are in place and at rest.

2. The combination, in a vehicle-top, of tracks or guideways for the side curtains arranged one above the other, the curtains mounted and adapted to be moved upon said tracks, said curtains being provided with stiffening-strips pivoted at their lower ends to fold together, and the means for supporting 40 said parts in their positions, substantially as set forth.

3. The combination, in a vehicle-top, of the bows, the covering, a lining under said bows formed free from the middle bow, and a transverse support conforming in shape to the upper portion of the middle bow and arranged below said lining, said support being adjustable whereby said lining may be forced up close to said middle bow or permitted to descend away from the same thereby leaving a free space for the manipulation of the side curtains, substantially as set forth.

In witness whereof I have hereunto set my hand and seal, at Arlington, Indiana, this 55 31st day of October, A. D. 1898.

DAVID SHIVELL. [L. S.]
